UNITED STATES PATENT OFFICE

154,057

DESIGN FOR A MANURE SPREADER

Noral A. Nelson, Royal Oak, Mich., assignor to
Harry Ferguson, Inc., Detroit, Mich., a corpora-
tion of Delaware

Application October 5, 1946, Serial No. 133,797

Term of patent 14 years

(Cl. D35—2)

To all whom it may concern:

Be it known that I, Noral A. Nelson, a citizen of the United States, residing at Royal Oak, in the county of Oakland and State of Michigan, have invented a new, original, and ornamental Design for a Manure Spreader, of which the following is a specification, reference being had to the accompanying drawing, forming a part thereof.

Figure 1 is a perspective view of a manure spreader, embodying my new design;

Fig. 2 is a top plan view; and

Fig. 3 is a side elevational view.

I claim:

The ornamental design for a manure spreader, substantially as shown.

NORAL A. NELSON.
